UNITED STATES PATENT OFFICE.

RUDOLPH KAUERT, OF SAN DIEGO, CALIFORNIA.

ATTACHMENT FOR UMBRELLAS.

1,255,757.

Specification of Letters Patent.

Patented Feb. 5, 1918.

Application filed August 13, 1917. Serial No. 185,991.

To all whom it may concern:

Be it known that I, RUDOLPH KAUERT, a citizen of the United States, residing at San Diego, in the county of San Diego and State of California, have invented a new and useful Attachment for Umbrellas; and I do hereby declare the following to be a full, clear, and exact description of the invention, such as will enable others skilled in the art to which it appertains to make and use the same.

This invention relates to an umbrella, and particularly to an improved attachment or locking device for engaging the outer extremities of the ribs when collapsed, to hold the umbrella locked.

The principal object of the invention is to provide a locking device for umbrellas to prevent people from appropriating or stealing umbrellas that do not belong to them. For instance on rainy days, should a person observe that an umbrella is locked, consequently cannot be opened for use, the temptation to steal the umbrella is greatly lessened.

A further object of my invention is to provide a locked holder for umbrellas, keeping the ribs thereof tightly closed without rolling the cover, hence preventing the silk cover from breaking in the creases.

A further object of the invention is to provide a push button to actuate the lock or latch, instead of by means of a key.

One of the objects of the invention is to provide an improved, simple and efficient device of this kind, which may be manufactured for a small cost, and sold at a reasonable profit.

A further object of the invention is the provision of a device comprising efficient and practical features of construction.

A further object of the invention is to provide a device consisting of two hingedly united sections of such curved contours as to encompass the ribs, and provided with means to hold the ribs in spaced relations, when they are collapsed, in combination with means for locking the two sections.

In practical fields the details of construction may necessitate alterations, falling within the scope of what is claimed.

The invention comprises further features and combination of parts as hereinafter set forth, shown in the drawings and claimed.

In the drawings:—

Figure 1 is a view in perspective of an

umbrella showing the ribs collapsed and the locking device or attachment applied.

Fig. 2 is an edge view of the locking device.

Fig. 3 is a plan view of the locking device.

Fig. 4 is a sectional view on line 4—4 of Fig. 2.

Fig. 5 is a detail plan view, showing a turn button for actuating the lock of the holder or attachment.

Fig. 6 is a plan view of another form of locking device showing parts broken away and parts in elevation, in order to illustrate another form of locking means.

Fig. 7 is a plan view of another form of an umbrella lid locking device.

Fig. 8 is an edge view of the locking device shown in Fig. 7.

Referring more especially to the drawings 1 and 2 designate two members of the locking device or fastener, one end of the member 1 is provided with a bifurcation 3, in which, on a pin 4, one end of the member 2 is pivoted. These members 1 and 2 are so curved as to conform to the contour of the stick 5 of the umbrella and the inner edge portions of these members 1 and 2 may or may not be provided with scallops 6 and 7, to receive the ribs of the umbrella when collapsed, as shown in Fig. 1 clearly. The member 2 has an extension 8^a, one edge of which is provided with ratchet teeth 8^b. The members of 1 and 2 are hollow as shown, in order to lessen the weight of said parts.

The member 1 at one end is provided with an opening 8^c to receive the reduced extension 8^a. Pivoted on a pin 8^e in the hollow part of the member 1 is a latch dog 8^g, the nose 9^a of which is designed to engage one of the teeth 8^b to hold the extension 8^a in the hollow part of the member 1. A spring 9^b secured at 9^c constitutes means to hold the nose of a latch dog in engagement with said tooth and also to hold the tail end of the latch dog in contact with the pin 9^e.

The wall of the member 1 is provided with a suitable key hole shaped opening 10^a, to receive a conventional form of key (not shown), whereby its tongue (not shown) may contact with the tail of the latch dog, in order to tilt the dog, whereby its nose may be disengaged from the tooth, consequently permitting the extension 8^a to be withdrawn from the member 1, and the two members 1 and 2 allowed to be

opened. In Fig. 5 a turn key 10° may be permanently carried by the member 1, so that its tongue may contact with the tail of the dog, in a manner similar to that previously set forth with regard to the key which is not shown.

In Fig. 6 another form of locking device is illustrated, and in this structure the members 1 and 2 are constructed so that they can be adjusted with relation to each other, to hold the ribs of the umbrella as tight or as loose as may be desired. Where the scallops on the member 2 of the structure shown in Fig. 6 terminate, one edge of the extension 8 (which corresponds to the extension 8^a) is provided with ratchet teeth 10. The member 1, at its free end merges into an enlarged portion 11. In other words, the member 1, in its curvature, tapers from the portion 11 toward and to the pivot 4. The enlarged portion 11 is provided with an opening 12, which is formed somewhat obliquely through the enlargement 11. The opening 12 and the extension 8 are correspondingly curved on an arc, using the pivot pin 4 as a center. In other words, the arc of opening 12 and the extension 8 are on a radius from the pin 4. By so curving the opening and the extension 8, the extensions 8 will pass readily through the opening, when the two members 1 and 2 are extended about the ribs of the umbrella, when the ribs are in engagement with the scallops. Adjacent the opening 12, the member 1 is provided with a hollow portion 13, in which the dog 14 is pivoted upon the pin 15. One end of the dog extends through an opening 16 in the wall 17, between the opening 12 and the hollow portion, so that the nose 18 of the dog may coöperate with the ratchet 10 of the extension 8. An abutment 19 is formed or provided on one of the walls of the hollow 13, and constitutes means to limit the tail 20 of the dog, there being a leaf spring 21 secured at 22 to hold the tail of the dog in contact with the abutment. Immediately following the arrangement of the two members 1 and 2 on the stick of the umbrella, so that the ribs may engage the scallops 6 and 7, substantially in the manner shown in Fig. 1, the extension 8 is passed through the opening 12, in which case the nose of the dog will ratchet over the teeth 10 against the action of the spring 21 until the ribs of the umbrella are clamped tight against the stick 5, and owing to the tail of the dog contacting with the abutment, the extension 8 will be held securely in position through the opening 12. However, by inserting a suitable key in the key opening 23 of the member 1, and turning the key in the direction of the arrow *a* so that the tongue member, not shown, of the key may contact with the tail of the dog, the nose of the dog may be thrown out of engagement with the teeth

10 of the extension 8, thereby allowing the extension 8 to be withdrawn from the opening 12, consequently permitting the removal of the locking device from engagement with the ribs of the umbrella. By means of a suitable chain 24 connected at 25 to the member 1, and at 26 to the umbrella stick, the locking device is carried by the stick of the umbrella, in order to always be handy for use. However, the locking device may be made detachable, or may be carried on the person, instead of carried by the umbrella.

In Figs. 7 and 8 the locking device comprises a body member 27 and a U-shaped member 28, the inner edge of the arch 29 of which is provided with a series of scallops 30. The body member 27 is provided with a segmental recess 31 having a series of scallops 32, which, and the scallops 30, receive the ribs of the umbrella, when it is collapsed. The body member 27 is provided with the openings 33 to receive the arms of the U-shaped member 28. The inner edges of the arms of the U-shaped member have teeth 34 and 35. The body member is hollow, and arranged in the hollow are the transverse bars 36 and 37, which are so arranged as to provide guides for sliding dogs 38, the noses 39 of which are beveled, so that the ratchet teeth will ratchet over the noses as the arms of the U-shaped member 28 are inserted through the openings 33. Springs 40 are carried by the pins 41, so that the ends of the springs will engage the pins 42 on said dogs, in order to hold the dogs in such wise that the abutments 43 of the dogs will contact with certain of the guide bars 36 and 37, thereby limiting the dogs in their outermost positions. The adjacent tail ends of the sliding dogs have laterally extending lugs 44, which may be engaged by the tongues, (not shown), of a key (not shown) but which may pass through the key opening 45 so as to actuate the dogs to disengage their noses from the ratchet teeth 34 and 35, thereby allowing the members 27 and 28 to be separated. The chain 24 in Figs. 3 and 4 is connected at 46 to the member 27.

The invention having been set forth what is claimed as new and useful is:—

In a lock for umbrellas, a pair of members pivotally united, said members being curved whereby they may engage about the ribs of an umbrella, the inner edges of said members being provided with scallops to engage the ribs to hold them in place, the separable ends of the members diagonally intersecting each other, one of said members having its separable end enlarged and provided with a diagonally arranged opening, through which the separable end of the other member diagonally passes, whereby said members may surround different diam-

eters of arrangement of ribs, said enlarged end of one member having a chambered out portion adjoining said diagonally arranged opening, the wall between the chambered out portion and the diagonal opening having an opening of communication between the diagonal opening and the chambered out portion, and a spring tensioned latch dog pivoted in said chambered out portion 10 and extending through the opening of communication, said member which passes through the diagonal opening having an extension provided with ratchet teeth to be

engaged by said latch dog to lock the members, said extension and the diagonal opening being curved concentric with the pivot between the two members, whereby said members may be adjusted to fit different diameters of umbrella rib arrangements. 15

In testimony whereof I have signed my name to this specification in the presence of 20 two subscribing witnesses.

RUDOLPH KAUERT.
